UNITED STATES PATENT OFFICE

AUGUST SCHWARZ, OF NUERMBERG, GERMANY, ASSIGNOR TO THE FIRM: J. S. STAEDTLER, OF NUERMBERG, GERMANY

DECORATING LEAD PENCILS

Application filed March 15, 1929, Serial No. 347,229, and in Germany October 29, 1927.

My invention relates to the stencilling of patterns upon lead-pencils, pen-holders and other rod-shaped objects. It is an object of my invention to provide means for simultaneously applying patterns to a plurality of pencils or the like.

To this end I mount on each pencil a suitable stencil and I impart rotary and, if desired, also transversal movement to all the 10 pencils, at the same time applying colour to those parts of the pencils, which are not covered by the stencils.

Any suitable means may be provided for applying colour, but preferably the colour 15 is applied by spraying.

In the drawings affixed to this specification and forming part thereof a device embodying my invention and specimens of patterns obtainable thereby are illustrated diagrammatically by way of example.

In the drawings

Fig. 1 is an elevation of a stencil and a pencil ready for insertion therein.

Fig. 2 is a cross section of a device for imparting transversal and rotary movement to the pencils,

Fig. 3 is a plan view showing one end of the device,

Figs. 4 and 5 illustrate specimens of patterns.

Referring to the drawings and first to Fig. 1, 1 is a stencil, 2, 2 are rings fixed to the ends of the stencil, and 3 is a lead-pencil, to be inserted in the stencil. The stencil here 35 shown consists of a helically wound strip of sheet metal or other suitable material to the ends of which rings 2, 2 are attached. The pencil 3 when inserted in the stencil is surrounded by the strip 1 and held in position 40 by the rings 2, 2 which may be split, if desired, to exert resilient pressure on the ends of the pencil.

In the practice of my invention I arrange 45 in parallel position a plurality of stencils, each having a pencil inserted therein. I then impart rotation and, if desired, also reciprocation to the stencils and apply colour to the uncovered parts of the pencils while they are being moved. After a predetermined 50 pattern has been produced, the stencils may

be exchanged for other stencils, for instance, a stencil having left-handed thread may be substituted for one having a right-handed thread. In this manner the chequered pattern shown in Fig. 4 is obtained, while Fig. 55 3 illustrates a pattern obtained with a single stencil as shown in Fig. 1.

The stencils may be caused to rotate without reciprocation or they may be displaced or reciprocated while rotating. It is not 60 always necessary to reciprocate the stencils as a single displacement at right angles to their axis may suffice for the production of the desired pattern.

During rotation and/or reciprocation of 65 the stencils colour is applied to them preferably by spraying. The spray is simultaneously applied to several juxtaposed pencils but in order to place a given number of pencils within reach of the spray the blanks may be displaced with respect to the spray nozzle, or the nozzle with respect to the spray, or both may be displaced. In performing the method with a movable spray nozzle the stencils are preferably moved in one direction only, for instance by a conveyer, while reciprocating movement is imparted to the stencils, when the spray nozzle is fixed. 70 75

Referring now to Fig. 2, 8 is a frame, 7 is a slide adapted to be reciprocated on the 80 frame by hand or by any suitable mechanism (not shown), 6 is a fixed plate inserted within the slide which is channeled for its reception, 5, 5 are races on the fixed plate 6, and 4, 4 are notched plates on the upper edges of 85 the slide 7. The stencils 1 encircling the pencils 3 are inserted with their rings 2, 2 in opposite notches of the plates 4, 4. When the slide is reciprocated the stencils are entrained by the notched plates 4, 4 and at the same 90 time rotated by contact with the stationary races 5, 5 on the plate 6, while colour is sprayed onto the pencils from the nozzle 9.

Any suitable means other than the rings 95 2 may be provided for holding the pencils in the stencils.

I wish it to be understood that I do not desire to be limited to the exact details of construction shown and described for obvi- 100

ous modifications will occur to a person skilled in the art.

I claim:-

1. An apparatus for stenciling rod-shaped objects comprising a stencil adapted to receive one of said objects, a frame, means on said frame for engaging the opposite ends of said stencil, a race for supporting said stencil, said race and said frame being adapted to be displaced with respect to each other, and means for applying coloring matter to said objects.

2. An apparatus for stenciling rod-shaped objects comprising a stencil adapted to receive one of said objects, a frame adapted to be reciprocated, means on said frame for engaging the opposite ends of a stencil, a fixed race for supporting said stencil while it is reciprocated by said frame, and means for applying coloring matter to said objects.

In testimony whereof I affix my signature.

AUGUST SCHWARZ.
